US00D739870S

(12) **United States Design Patent**
Roberts et al.

(10) **Patent No.:** **US D739,870 S**
(45) **Date of Patent:** ** *Sep. 29, 2015

(54) **DISPLAY SCREEN WITH GRAPHICAL USER INTERFACE**

(71) Applicant: **Microsoft Corporation**, Redmond, WA (US)

(72) Inventors: **Chad Michael Roberts**, Snohomish, WA (US); **Andrea Michelle Simons**, Shoreline, WA (US); **Janis J. Lee**, Kirkland, WA (US)

(73) Assignee: **Microsoft Corporation**, Redmond, WA (US)

(*) Notice: This patent is subject to a terminal disclaimer.

(**) Term: **14 Years**

(21) Appl. No.: **29/462,873**

(22) Filed: **Aug. 9, 2013**

(51) LOC (10) Cl. **14-04**

(52) U.S. Cl.

USPC **D14/487**

(58) **Field of Classification Search**

USPC D14/485-495, 448; 715/700, 702, 716, 715/719, 726, 733, 763, 765, 781, 783, 864

(57) **CLAIM**

The ornamental design for a display screen with graphical user interface, as shown and described.

DESCRIPTION

FIG. 1 is a front view of a display screen with graphical user interface showing the new design; and,

FIG. 2 is another front view thereof.

The broken line showing of the device in FIG. 2 illustrates environment and the remainder of the broken lines in FIGS. 1 and 2 represent portions of the display screen with graphical user interface; the broken lines form no part of the claimed design.

1 Claim, 2 Drawing Sheets
